UNITED STATES PATENT OFFICE.

GEORGE C. SCHMITZ, OF RACINE, WISCONSIN, ASSIGNOR TO THE McCRUM-HOWELL COMPANY, A CORPORATION OF CONNECTICUT.

DESIGN FOR A PNEUMATIC-CLEANER CASING.

43,380.

Specification for Design.

Patented Dec. 24, 1912.

Application filed November 4, 1910. Serial No. 590,765. Term of patent 14 years.

To all whom it may concern:

Be it known that I, GEORGE C. SCHMITZ, a citizen of the United States, and a resident of Racine, county of Racine, State of Wisconsin, have invented a new, original, and ornamental Design for a Pneumatic-Cleaner Casing, of which the following is a specification, reference being had to the accompanying drawing, forming a part thereof.

The figure is a perspective view of a pneu-

matic cleaner casing, showing my new design.

I claim:

The ornamental design for a pneumatic cleaner casing, as shown.

GEORGE C. SCHMITZ.
